Atty.

UNITED STATES PATENT OFFICE

WILHELM VORWERK, OF BARMEN, GERMANY

HOSE SUPPORTER

Application filed July 22, 1929, Serial No. 380,088, and in Germany August 1, 1928.

My invention relates to hose supporters of the type in which the marginal portion of a sock or hose is held between a clasp and a button on a pad. It is an object of my invention to improve supporters of this type in which the button is made integral with the pad forming an extension of the pad and to this end I make the button and the strap with which it is integral as an independent unit which may be separated from the pad and therefore is readily exchangeable.

Heretofore hose supporters had to be scrapped when their buttons were worn notwithstanding all other parts being in good condition.

In reducing my invention to practice I provide the usual button and clasp for engaging the marginal portion of the sock or stocking but I so design the unit comprising the button and strap that it is readily exchangeable. I may either provide a strap-and-button unit with an extension adapted to be secured to a pad or other means connecting it with a leg band or I may secure the unit to a ribbon which in turn is secured to the pad, the unit being for instance, inserted in a pocket of the ribbon.

In the drawings affixed to this specification and forming part thereof two devices embodying my invention are illustrated diagrammatically by way of example.

In the drawings

Fig. 1 is an elevation of a button-and-strap unit which is provided with an extension adapted to be secured to a loop or the like which in turn is connected with the leg band through the medium of the usual pad or the like.

Fig. 2 is an elevation showing the unit inserted in a pocket of a ribbon, and

Fig. 3 is an end elevation of the unit viewed from the left in Fig. 1 and partly in section on the line 3-3 in Fig. 1.

Fig. 4 is an end elevation of the ribbon and the unit, viewed from the left in Fig. 1.

Referring now to the drawings and first to Figs. 1 and 3, 7 is a button, 7a is a strap with which the button is made integral, 5 is a bracket having end flanges 5a and a clamp 9 pivoted in the flanges at 9' adapted to engage

an extension at the upper end of the unit 7, 7a which is threaded through the bracket and secured by the clamp 9, 6 is a clasp hinged in suitable bearings at the base of the bracket 5, and 8 is a loop which is supported in suitable bearings at the top of the bracket and serves for attaching the bracket to a leg band, not shown, through the medium of a suitable pad or other intermediate member, not shown.

The bracket 5 may be dispensed with by making the loop 8 and the clasp 6 in a single part, the clamp 9 being arranged on this part intermediate its loop and clasp portion, or by directly pivoting the loop on the clasp. Obviously, there are other ways of attaching the units to the part or parts by which it is connected with the leg band, and Figs. 2 and 4 only illustrate an example.

Referring now to these figures, they illustrate a unit which is inserted in or secured to a ribbon 11 which is threaded through the loop 8 and fixed thereto by means of the clamp 9 which is pivoted in the flanges 5a of the bracket 5 at 9'. Preferably this ribbon has a pocket-shaped member 10 with a button hole on one side, and a flap for concealing the button 7. Its ends may be fringed to prevent them from fraying. The unit is so disposed in the pocket 10 that only the head of the button projects from the pocket. The flap improves the appearance of the device.

It is evident that the unit may be designed in other ways than herein described, the essential feature being its exchangeability, and therefore I wish it to be understood that I do not desire to be limited to the exact details of construction shown and described for obvious modifications will occur to a person skilled in the art.

I claim:

1. A hose supporter comprising a bracket, a clasp on said bracket, a ribbon adapted to be threaded through said bracket so as to cover both sides of said bracket, means for securing said ribbon in said bracket, a button comprising a base plate and a head projecting therefrom and adapted to be engaged by said clasp, a pocket in said ribbon for the reception of said buttonhead-and-base-plate unit, with the base plate concealed in said pocket.

and the buttonhead projecting therefrom, and a flap on said ribbon extending beyond said bracket and adapted to conceal said buttonhead.

- 5 2. A hose supporter comprising a bracket, an eye on said bracket for the reception of a clasp, upturned ears on said bracket, said upturned ears engaging the sides of said clasp so as to hold them in said eye, a ribbon adapted to be threaded through said bracket so as to cover both sides of said bracket, a clamp supported in said upturned ears for securing said ribbon in said bracket, a button comprising a base plate and a head projecting therefrom and adapted to be engaged by said clasp, a pocket in said ribbon for the reception of said buttonhead-and-base-plate unit, with the base plate concealed in said pocket and the buttonhead projecting therefrom, and a flap on said ribbon extending beyond said bracket and adapted to conceal said buttonhead.

In testimony whereof I affix my signature.

WILHELM VORWERK.
